(57) **CLAIM**

The ornamental design for a profiled baluster for railing, as shown and described.

DESCRIPTION

FIG. 1 is a perspective view of a profiled baluster in a railing showing my new design;

FIG. 2 is a front and side perspective view of a baluster for railing showing my new design;

FIG. 3 is a perspective view of a profiled baluster; and,

FIG. 4 is a cross sectional view taken along line IV-IV in FIG. 1.

The broken lines are for illustrative purposes only and form no part of the claimed design.
